United States Patent Office

Des. 220,313
Patented Mar. 30, 1971

220,313

PACKAGING CONTAINER

Stafford D. Collie, Kansas City, Mo., assignor to Phillips Petroleum Company

Filed Jan. 12, 1970, Ser. No. 20,893

Term of patent 14 years

Int. Cl. D9—04

U.S. Cl. D9—185

FIG. 1

FIG. 2

FIG. 3

FIG. 4

FIG. 5

FIG. 1 is a top plan view of a packaging container showing my new design;

FIG. 2 is a side elevational view thereof, the side opposite being a mirror image thereof;

FIG. 3 is a rear end elevational view thereof;

FIG. 4 is a front end elevational view thereof; and FIG. 5 is a bottom plan view thereof.

I claim:

The ornamental design for a packaging container, as shown and described.
